UNITED STATES PATENT OFFICE.

CLARENCE E. FLORKEY, OF DAYTON, OHIO, ASSIGNOR TO THE SCHIEBLE TOY AND NOVELTY COMPANY, OF DAYTON, OHIO, A CORPORATION OF OHIO.

WHEELED TOY.

Original application filed November 3, 1922, Serial No. 598,902. Divided and this application filed October 8, 1923. Serial No. 667,378.

To all whom it may concern:

Be it known that I, CLARENCE E. FLORKEY, a citizen of the United States, residing at Dayton, in the county of Montgomery and State of Ohio, have invented certain new and useful Improvements in Wheeled Toys, of which the following is a specification, reference being had therein to the accompanying drawing.

10 My invention relates to toys, and in particular to power toys.

It is the object of my invention to provide a toy representing an automobile which can be economically manufactured in 15 quantities out of a minimum number of pieces.

It is my object to provide a toy which will be rigid and strong and which will be adaptable to a pull toy and also be adaptable to a power toy which is preferred. The source of power is immaterial, but I prefer to employ a friction drive.

It will be understood that in the manufacture of toys where the amount of profit 25 per toy is small it is essential that the production be in large quantities through dies. Because of the great expense of the dies, it is necessary to reduce the number of parts of any toy to the minimum. It is also essential to reduce the amount of stock used 30 so that it is a matter of considerable importance to economically utilize the stock and design the several parts so that there will be the least waste.

35 It is also essential to have the toys simulate the appearance of actual articles of commerce as nearly as possible.

It is the object of my invention to provide a one piece frame, hood, body members, body side walls, and bumper support 40 upon which there can be interchangeably mounted a roadster top and body, or a sedan top, or a coupé body.

It is a further object to provide a rear 45 deck seat and floor board member which can be used for both the coupé and roadster equipments.

It is an additional object to provide a 50 blank so laid out that when it is finally formed the side walls of the body and frame will be parallel while the hood will have its side walls approaching one another towards the front and its top wall descending to

wards the front where the radiator is located.

It is a further object of my invention to provide such a lay out of blanks and dies that the minimum number of forming and piercing operations will be necessary.

It is an additional object to provide an 60 interchangeable wind-shield.

It is an object to provide a fender which may be readily attached and detached for shipment and which will have its ends so concealed by the wheels that they will not 65 catch against the hands of the children operating the toys or catch in their clothes.

It is a further object to provide a one piece reinforced radiator which simulates the radiator on an automobile.

70

Referring to the drawings:

Figure 1 is a plan view partially in perspective of the toy having a coupé body;

Fig. 2 is a plan view of the body blank 75 in its initial stage;

Fig. 3 is a plan view of the body blank with the doors, louvers, and edges of the frame formed;

Fig. 4 is a plan view partially in perspective showing the body blank formed to 80 provide the double tapered hood, side frame members, and the side walls of the body.

Fig. 5 is a plan view of the rear deck body blank which is used to form the rear deck, seat, floor board, and dash board;

85

Fig. 6 is a perspective of the complete article made from the blank of Fig. 5;

Fig. 7 is the radiator blank;

Fig. 8 is the completed radiator;

Fig. 9 is the blank for the running board 90 and fender on one side of the car;

Fig. 10 illustrates the blank after the first forming operation;

Fig. 11 represents the blank after the last forming operation;

95

Fig. 12 represents the lamp blank;

Fig. 13 represents the completed lamp;

Fig. 14 is the wind-shield, dash board, and sun shade blank;

Fig. 15 is a perspective of the blank finally formed;

100

Fig. 16 is the coupé body blank;

Fig. 17 is a coupé body blank just prior to having the parts assembled;

Fig. 18 is a perspective of the assembled 105 coupé body looking at a rear corner;

Fig. 19 is a perspective looking from the front corner of the assembled body, showing the wind-shield member, sun shade, etc., in position.

5 It will be understood that the primary purpose of this invention is to provide in a few pieces a toy which may be shaped to exactly resemble an automobile. The problem which I have solved has been to select 10 the minimum pieces which can by successive die operations assume in single blanks a number of different configurations. It is also necessary to have the parts interchangeable as far as possible, such as the fenders 15 and the dies interchangeable as in the case of the dies for the fenders. It will be realized that my invention is applicable not only to toys but to the manufacture of other articles such as automobiles, whereas in a 20 cheaper class of vehicles the same problems are presented and the same economies are necessary.

Referring to the drawings, and in particular to Figures 2, 3, and 4:—

25 1 is a blank having two diverging side wall portions 2. The forward corners of the blank are provided with ears 3 and apertures 4. These ears later form the front ends of the automobile frame. The 30 axes of the automobile pass through the apertures 4. The curved edges 5 of the portions marked 2 of the blank form the upward edges for supporting the rear deck of the automobile to be hereinafter described. 35 The cutaway portions 6 and 7 on the other side of these side wall portions 2 are provided for receiving the rear axle and actuating mechanism.

40 On either side of the blank about half way the length thereof V-shaped slots or notches 8 are cut to permit of the formation of the forward part of the blank into an automobile hood. Louvers 9 are formed on either side of the blank near the forward 45 end while the blank is struck up along the line 10 to form the side walls of the hood. The hood tapers downwardly and inwardly towards the forward end. A flange 11 is formed along the lower edge of the frame. 50 An embossed U-shaped portion 12 is formed on the side walls of the blank to indicate the doors.

The blank is finally formed as in Fig. 4 55 with the tapering hood and the side walls converging to one another. The ends of the frame members are pierced as at 13 for receiving a suitable bumper. When the blank is formed up into the completed shape shown in Fig. 4 a ledge 14 of triangular 60 shape is located at the base of the hood.

Wheels 15, mounted on axle 16, are attached to the body. The rear deck as seen in Figs. 5 and 6 as well as the seat and floor board and dash board of the vehicle are 65 formed of a single piece consisting of a rec-

tangular portion 17 having notches near its rear end at 18.

A narrower portion of the blank 19 is formed integral with the rectangular portion 17. It tapers slightly towards the front 70 end and is provided on either side with ears 20.

When the blank is formed it consists of the portion marked 21 which is the strip bent over at the rear end of the deck to form 75 a finished rear edge. It is also formed of the arched portion 17 with right angle flanges 22 which overlap the side walls 2 on the curved edges 5. It also consists of the back of the seat 23, the seat 24, the heel 80 board 25, the floor board 26, and the dash board 27.

When the body is so assembled a spare wheel 28 is mounted by a clip 29 on the rear deck, the clip passing through the 85 aperture 30.

90 A radiator blank 31 is formed, as in Fig. 8, with louvers 32 overlapping flanges 33 in a semicircular cap portion 34 with a flange 35.

The fenders are formed as follows:

A strip of metal 36 is provided at one 95 end with a series of teeth 37. Midway its length it is provided with a rectangular projection 38 and at its forward end it is provided with a series of teeth 39, 40, 41, and 42, the outline of which is triangular. As will be seen in Fig. 10, the teeth in either end, as well as the rectangular edge 43, are formed at right angles to the main body 36 of the blank. The ends of the blank are then curved as at 44 and 45 into the arched rear and front fenders, the teeth and flange being used to engage with the main body blank to which the fenders are welded or 105 riveted.

110 Head lamps formed of the blank 46 into the cups 47 are mounted on the front fenders.

A wind-shield blank, shown in Fig. 14, is 115 provided with a convex upper edge 48 to fit beneath the curved roof of the coupé body. It is provided with a concave edge 49 to fit on the convex top of the hood. Its edges on either sides, as at 50, are parallel to one another. An I-shaped aperture 51 is cut in the blank 52. One portion of the material 53 adjacent the I-shaped aperture is bent inwardly to form a ledge over the dash board and the opposite portion of the blank 120 is bent outwardly as at 54 to form a sun shade.

The coupé body itself consists of a top portion 55 having rounded forward corners 56 and a front edge 57. It has rounded rear corners 58 and a rear panel 59 with a rear window 60. On either side there is integrally formed with the top side wall blanks 61 and 62 having windows 63 and 64. The outer edge of this blank is semicircular as 130

at 65 and is provided with a plurality of teeth 66.

In Fig. 17, the blank will be seen in the last stage before final formation. Flanges 5 67, 68, and 69 are formed on the sides of the top to overlap the adjacent edges of the side walls when the side walls are bent at right angles to the top. The side walls are embossed with door frames 70 and the windows 19 are punched inwardly so that flanges 71 are formed. The side walls themselves 15 are formed into semicircular portions, while the teeth 66 are bent at right angles along the straight line 72. The faces of the teeth 15 which were originally laid out on a straight line are now laid out on a curved line 73. The faces 74 of the teeth are in a straight line in the same plane so that they will fit within the straight side walls of the body. 20 When the side walls are bent at right angles to the top and the panels 59 are bent at right angles to the top and the several edges are overlapped and welded a unitary body is formed which when mounted upon the chassis 25 hereinbefore described forms the coupé. This coupé body is seen in Figs. 18 and 19.

It will be understood that I do not desire to be confined to the details of my invention, but comprehend within it suitable 30 modifications which may be found convenient in adapting my invention to varying conditions.

This application is a division of application Ser. No. 598,902.

Having thus fully described my invention, what I claim as new and desire to secure by Letters Patent, is:—

1. A blank for the bodies of toy vehicles 40 formed from a single piece of sheet metal and comprising a central portion having its main portion shaped to conform to the top of the toy vehicle, an end extension shaped to form the rear of the vehicle body and provided with a window opening, and side wings each formed integrally with the center 45 of one side of the main portion of the central portion and provided with door and window openings.

2. A blank for the bodies of toy vehicles

formed from a single piece of sheet metal 50 and comprising a central portion having its main portion shaped to conform to the top of the toy vehicle, an end extension shaped to form the rear of the vehicle body and provided with a window opening, and side 55 wings each formed integrally with the center of one side of the main portion of the central portion and provided with door and window openings, the peripheral portions of said blank being provided with notched 60 flanged forming extensions adapted for connection to other portions of the toy.

3. A blank for the bodies of toy vehicles formed from a single piece of sheet metal and comprising a central portion having its 65 main portion shaped to conform to the top of the toy vehicle, an end extension shaped to form the rear of the vehicle body and provided with a window opening, and side 70 wings each formed integrally with the center of one side of the main portion of the central portion and provided with door and window openings, the peripheral portions of said blank being provided with notched flange forming extensions adapted for connection to other portions of the toy, the wings and end extension of said blank being bent downwardly at right angles to the main top to form the sides and ends of the vehicle body.

4. A blank for the hoods of toy automobiles consisting of a single piece of sheet metal comprising a main portion of general rectangular shape having a pair of short extensions at one end and a pair of 85 long extensions at its other end, the long extensions being of substantially the same width as the sides of the hood to be formed from said blank and having their outer edges notched to engage with cooperating 90 portions of other blanks, the main portion being provided with slits to represent the ventilation openings of an automobile hood, and the forward position of said hood being tapered downwardly and inwardly.

In testimony whereof, I affix my signature.

CLARENCE E. FLORKEY.
